JAMES L. JUDGE,
INVENTOR

BY *Chas. Beins*
His ATTORNEY.

UNITED STATES PATENT OFFICE.

JAMES L. JUDGE, OF MINNEAPOLIS, MINNESOTA.

SEAL FOR STEAM-RADIATORS.

SPECIFICATION forming part of Letters Patent No. 741,503, dated October 13, 1903.

Application filed May 28, 1903. Serial No. 159,199. (No model.)

To all whom it may concern:

Be it known that I, JAMES L. JUDGE, a citizen of the United States, residing at Minneapolis, in the county of Hennepin and State of Minnesota, (whose post-office address is No. 2645 Third avenue south, Minneapolis, Minnesota,) have invented a new and useful Improvement in Seals for Steam-Radiators, of which the following is a specification.

10 My invention relates to improvements in steam-radiators wherein the steam is conducted to the radiator by one pipe and the condensation thereof returned to the boiler by a separate return-pipe; and the object of 15 my improvement is to provide a seal in connection with the said return-pipe and the radiator for the purpose of preventing steam from entering the return-pipe so as to produce "pounding" or "snapping" and to conduct the air from the radiator without the use 20 of an air-valve or independent air-pipe for each radiator, notwithstanding a system of radiators are connected upon the same feed and return pipes. I attain these objects by 25 the mechanism shown in the accompanying drawings, in which—

Figure 1 is a steam-radiator with my device connected with the return-pipe thereof. Fig. 2 is a vertical section of a right-and-left 30 nipple attached to the adjacent part of the radiator and which nipple contains my devices. Fig. 3 is an end view of said right-and-left nipple looking from the outer end of said nipple shown in Fig. 2.

35 Similar numerals refer to the same parts throughout the several views.

The steam-radiator 1 has leading therefrom in the usual manner and for the well-known purpose the return-pipe 2, said pipe being 40 provided with the usual cock or valve 3. A right-and-left nipple 4 connects the radiator 1 with the valve 3 and return-pipe 2. The inner end of said nipple projects into the radiator 1 beyond the walls thereof, and the 45 inner end of said nipple 4 is closed, as shown in Fig. 2. At the lower side of the inner projecting end of said nipple 4 is an opening 5 and at the upper side of said end an opening 6, both leading from the interior of the radiator to the interior of the nipple. At the 50 lower side of said nipple 4, within the same and between the opening 5 and the outer ex-

tension of the nipple, is a shelf 7. This shelf may be provided with a small drip-opening 8 at its base.

The operation of my seal is as follows: The steam is introduced to radiator 1 through the ordinary steam-conducting pipe 9. The air is driven out through the return-pipe 2. Condensation immediately occurs within the radiator and collects as water in the bottom thereof. The flow of this water through the return-pipe 2 is held back and prevented by the shelf 7, except such small portions as escape through the small drip-hole 8, while further discharge 65 of air and the discharge of steam from the radiator through opening 5 is prevented by the sealing or closing of that opening by the water in the bottom of the radiator. The discharge of said air continues through the 70 opening 6 into the nipple and thence out through the return-pipe 2. It is obvious that steam may also escape from the radiator through opening 6. In the meantime the water collecting in the bottom of the radiator 75 enters the nipple 4 through opening 5, gradually rises to the top of shelf 7, and flows off over said shelf through the return-pipe. By means of the opening 6 the pressure upon 80 the column of water within the passage leading from opening 5 to the top of shelf 7 and which is held back by the shelf 7 is so far equalized with the pressure on the water in the radiator as to prevent the water from being forced out through opening 5 over the 85 shelf 7, so as to remove the seal. In other words, a passage is formed leading from the opening 5 into the return-pipe over the top of shelf 7, the inner opening of which passage is lower than the discharge end thereof, and 90 the opening 6 leads from the radiator at a point higher than the discharge end of said passage. Hence opening 5 is kept continually sealed against the passage of steam while the radiator is in use, the water is permitted 95 to flow from the radiator as rapidly as necessary, and the steam is held back to escape through the small opening 6 only, so that snapping or pounding is impossible. Moreover, such escaping steam being compelled to enter the nipple 4 and the return-pipe through a 100 small opening, such as 6, is almost immediately vaporized, so that by my seal I have the return of water and air only through the re-

- turn-pipe 2. When the radiator is not in use, the drip-hole 8 finally lowers the water in the bottom of the radiator to the level of that opening, so as to prevent damage from freezing.
- 5 The use of the air-valves on the radiator opening into the room causes discoloration of the walls and disagreeable odors. My devices dispense with such air-valves and all independent air pipes or valves for each radiator.
- 10 A system comprising a large number of radiators may be connected upon a common feed and return pipe, when my devices will work perfectly, as described. The condensation may be returned to the boiler through
- 15 the return-pipe, and the air may be allowed to escape at the boiler through a single air-valve which will serve all the radiators upon the said system.
- It is obvious that the nipple 4 forms a portion of the return-pipe 2. Hence my devices may be referred to as connected directly with the return-pipe.
- What I claim as new, and desire to secure by Letters Patent, is—
- 25 1. In combination with a steam-radiator, of the return-pipe having a passage leading from the lower part of the radiator into the return-pipe through the lower portion of said return-pipe, and a shelf located at the lower side of
- 30 the interior of the return-pipe and between said opening and the outer extension of the return-pipe, said return-pipe being further provided with a separate opening leading from the radiator at a point above said passage, substantially as specified.
- 35 2. In a steam-radiator, the combination with the radiator, of the return-pipe projecting into the same, and a shelf in said return-pipe, said return-pipe having its inner end closed and having a passage from the lower portion of the radiator into the return-pipe and leading over said shelf, said passage being adapted for conducting water from the radiator into the return-pipe and being so arranged that the inner opening of said passage from the radiator is lower than the outer, discharge end of said passage in said return-pipe, and said return-pipe being further provided with an opening leading from the radiator into the return-pipe at a point higher than said shelf, substantially as herein set forth.
3. In connection with a steam-radiator, the combination of the radiator, the return-pipe projecting into the same, said return-pipe having its inner end closed and provided with two openings leading from the radiator into the inner, projecting end of said return-pipe, one opening thereof being at the lower side and the other opening being at the upper side of said projecting end, and a shelf located at the lower side of the interior of the return-pipe and between said first-named opening and the outer extension of the return-pipe, said shelf being provided with a drip-hole at the base of said shelf, substantially as shown and described.

JAMES L. JUDGE.
